FLASHLIGHT SUSPENSION

John Thomas Powell, Washington, D. C.

Application November 19, 1945, Serial No. 629,454

1 Claim. (Cl. 224—5)

1

This invention relates to flash lights.

An object of this invention is to provide in a flash light structure means for suspendingly carrying the structure, said means being of an extensible character whereby the structure may be carried in a hand or supported from the neck of the user.

Another object of this invention is to provide a suspension means for a flash light which includes a flexible member, and spring-pressed winding means fixed to the flash light housing for the flexible member so that the latter can be extended or retracted as may be desired.

A further object of this invention is to provide in combination with a flash light structure, an extensible bail so that the flash light structure may be carried in a selected position.

To the foregoing objects, and others which may hereinafter more fully appear, the invention consists of the novel construction, combination and arrangement of parts, as will be more specifically referred to and illustrated in the accompanying drawings, but it is to be understood that changes, variations and modifications may be resorted to which fall within the scope of the invention as claimed.

In the drawings:

Figure 1 is a detail front elevation of a flash light structure embodying this invention,

Figure 2 is a detailed rear elevation of the device with the bail or suspension member retracted,

Figure 3 is an enlarged sectional view taken on the line 3—3 of Figure 2,

Figure 4 is a fragmentary sectional view taken on the line 4—4 of Figure 3, and

Figure 5 is a detail rear elevation of a modified form of this invention.

Referring to the drawings, the numeral 10 designates generally a flash light structure embodying a housing 11 within which batteries are positioned for energizing the light bulb 12. The light bulb 12 is controlled by movement of a switch 13 which extends from one side of the housing 11.

In order to provide a means whereby the housing 11 may be suspendingly carried from either the hand or neck or other position, I have provided a flexible suspension member or bail 14. The suspension member 14 has one end thereof fixed as at 15 to the rear wall of the housing 11. The suspension member 14 is extended along the rear wall of the housing 11 and is then looped and slidably mounted through a guide 16 fixed to the rear of the housing 11. The suspension member 14 is wound on a spring-pressed drum or reel 17

2

which is rotatably mounted in a winding drum housing, generally designated as 18.

The housing 18 includes complementary telescoping housing members 19 and 20 within which the reel or drum 17 is rotatably mounted. A hollow shaft 21 is carried by the housing 18 being crimped, as at 22, at its outer end to hold the complementary housing members 19 and 20 together. The reel or drum 17 includes an inner plate 23, 10 which is formed with a plurality of ratchet teeth 24. A ratchet pin 25 is loosely mounted through a pair of slots 26 formed in the hollow shaft or stud 21 and is fixed to a releasing pin 27 loosely mounted in the hollow shaft 21 and extending 15 from one end thereof. A spring 28 engages about the hollow shaft 21 and bears against the pin 25 so as to constantly urge the ratchet pin 25 in locking position with respect to the ratchet teeth 24. An elongated spring 29 is disposed in a barrel 30 20 formed with the reel or drum 17, being fixed at one end to the hollow shaft 21 and fixed at the other end to the reel or drum 17. The flexible member 14 is extended through an opening 31, which is formed in the housing 18 and then passes 25 loosely through the guide 16.

Referring now to Figure 5 there is disclosed a modified form of this invention embodying a pair of reel or winding members 18a and 18b which are fixed to the rear wall of the housing 11a. 30 A common flexible suspension member 14a is connected to the two reel members 18a and 18b being extended loosely through guide members 16a fixed to the rear of the housing 11a.

In the use and operation of this flash light structure the extensible bail or suspension member 14 may be slightly extended above the top of the housing 11 so that the suspension member 14 may be grasped in one hand for carrying the flash light structure in a hand. The housing 11 35 may be disposed at any desired distance below the hand by merely pulling the flexible member 14 upwardly thereby unwinding the flexible member 14 from the reel 17 and at the same time tensioning the spring 29. The ratchet pin 25 will release 40 ably hold the reel 17 in any extended position of the suspension member 14. If it is desired to extend the suspension 14 a substantial distance from the housing 11 to dependingly support the flash light structure from the neck the suspension member may be extended, as shown in Figure 1. By supporting the flash light as shown in Figure 1, the user may have the free use of both hands while obtaining the desired light from the flash light. The suspension member 14 may be 45 made from an elongated metal strip having a de-

gree of resiliency or may be formed from fabric or other flexible material.

What I claim is:

In combination, an article to be supported, a flexible bail for suspensably supporting said article, and a pair of spring actuated take-up reels, each having secured thereto one end of said bail, said reels carried by said article and secured thereto, whereby said article may be readily and adjustably positioned on the person of a user or conveniently mounted at various selected heights of a support.

JOHN THOMAS POWELL.
